CLAIM

(57) I claim the ornamental design for a light, as shown and described.

DESCRIPTION

FIG. 1 is a perspective view of an inventive light.

FIG. 2 is a first side view of the light of FIG. 1.

FIG. 3 is a second side view of the light of FIG. 1, opposite that of FIG. 2.

FIG. 4 is a top view of the light of FIG. 1.

FIG. 5 is a bottom view of the light of FIG. 1.

FIG. 6 is a rear view of the light of FIG. 1; and,

FIG. 7 is a front view of the light of FIG. 1.

The broken lines shown herein are for illustrative purposes only and form no part of the claimed design.
